MOLD STRUCTURE

Johannes T. Sentrop, Wyoming Township, Kent County, Mich.

Application February 28, 1936, Serial No. 66,188

12 Claims. (Cl. 25—41)

The present invention relates to mold or form structures for making concrete blocks and the like, and its object is, generally, to provide such a structure having a mold or form whose sides or walls may be readily separated to remove the molded work; and more particularly to provide such a mold having an inner wall adjustable relatively to an adjacent outer wall of the mold; and further, to provide such a mold having sides or walls swingably connected; and further, to provide simple and effective means for releasably securing said walls in their position of use; and further, to provide such a structure on which the mold is turnable to a position wherein the work may be readily removed.

These and any other and more specific objects hereinafter appearing are attained by, and the invention finds a preferable embodiment in, the illustrative structure particularly described in the body of this specification and illustrated by the accompanying drawings, in which:

Figure 1 is an elevational right hand side view of my structure for forming concrete blocks and the like, showing the parts in their cooperative position of use;

Figure 2 is a top plan view thereof, certain parts being broken away;

Figure 3 is an elevational rear view of the same, certain parts being broken away;

Figure 4 is an elevational front view of right hand side upper portions of the structure;

Figure 5 is a view similar to Figure 1 but showing the rear wall of the structure swung rearwardly and middle parts broken away;

Figure 6 is an elevational right hand side view thereof showing the form or mold portion of the structure turned forwardly, and lower portions broken away;

Figure 7 is an elevational front view of the same, showing said form or mold portion turned forwardly, the side walls swung open, the inner wall swung somewhat rearwardly and the molded concrete block and the plate or templet withdrawn;

Figure 8 is a view in perspective of a concrete block formed in this structure;

Figure 9 is an elevational right hand side view of a modified construction, with its rear wall swung rearwardly;

Figure 10 is an elevational rear view of upper portions thereof, certain parts being shown in vertical section taken on line 10—10 of Figure 9;

Figure 11 is a view in perspective of a concrete block formed in this modified construction.

The embodiment of the invention illustrated

by these drawings is a structure for forming or molding concrete blocks and the like. This structure includes a support or base portion desirably comprising a pair of metal castings 1 connected by horizontal threaded rods 2, 3. The form or mold portion carried by this base comprises a bottom 5 pivotally mounted on the rod 3 to swing about a horizontal axis, opposite side walls 6 pivotally mounted at 7 on the bottom to swing about an axis at right angles to said rod, 10 a front wall 8 pivotally mounted at 9 on rod 3, and a rear wall 10 having long arms 11 pivotally mounted at 4 on the castings 1.

These walls are desirably metal castings with strengthening ribs as shown and are releasably held in the use position shown in Figures 1, 2, 3, and 4 by suitable means, as follows: A pair of rods 13 at the opposite sides 6 of the mold are turnable on the spindles 14 of blocks which have spindles 15, at right angles to the spindles 14, 20 turnable in bearings in the rear wall's ears 16.

The free front ends of these rods 13 are received into notches or sockets 17 in the front wall, and are threaded so that their nuts 18 may be turned into contact with the outer side of the 25 front wall to hold the front and rear walls tightly in their use position. The side walls 6 are releasably held in said use position by hook catches 19 engaging the front wall 8 and similar catches 20 engaging the hereinafter described 30 inner wall 21 of the mold. The side walls are also held by the rods 13 which wedgingly engage their upwardly-inwardly inclined ribs 51.

The rear wall 10 carries on its inner side the core or cores 22 secured thereto by threaded 35 bolts 23 extending through the cores' outwardly projecting lugs 24 and having nuts 25 contacting the inner side of the cores' flanges 26. An inner wall 21 (forming the actual rear wall of the form of mold) has its arms 31 pivotally mounted at 27 on the bottom 5 and has stops 28 threaded in the inner wall's rearwardly projecting bosses 29, the heads 30 of these stops, when the stops are turned to desired position, engaging the inner surface of the rear wall 10 to hold said rear and inner walls in desired adjusted position. This inner wall has curved notches 32 extending downwardly from its upper edge, in which notches the cores 22 fit at their under and lateral sides. A flat plate or templet 33 is placed 40 in contact with the front wall's inner surface (or its inwardly extending ribs 34 as shown), this plate forming the actual front wall of the mold or form.

The parts being in the use position shown in 45

- Figures 1, 2, 3 and 4, except that the rear wall 10 is swung back to withdraw the cores, concrete is poured into the open top of the mold for forming the concrete block 35 shown in Figure 8, whose pits 36 (for the engagement of suitable handling tools) are formed by the inward projections 37 of the side walls 6 and whose rabbet 38 is formed by a molding strip 39 on the inner side of the plate 33 adjacent its lower edge as indicated in Figures 1, 2 and 5. When the mold is filled to the level of the bottom of the notches 32 the rear wall 10 with the cores 22 is swung forwardly and the mold is completely filled.
- 15 When the form is filled, the nuts 18 are loosened, the rods 13 swung upwardly out of the notches 17 of the front wall 8 and then outwardly, the rear wall 10 with the cores 22 swung rearwardly, the hook catches 19, 20 are released and the side walls 6 are swung outwardly and the inner wall rearwardly. The form or mold portion of the structure is turned on the rod 3 upwardly and forwardly to resting position on the front brackets 49 as shown 20 in Figures 6 and 7. This brings the molded block 35 to a position wherein it rests on the now horizontal plate or templet 33 so that the block with said plate may be readily removed upwardly or horizontally from the structure.
- 25 30 In the modified construction illustrated in Figures 9 and 10 (wherein the concrete block 41 shown in Figure 11 is formed), the inner wall 21 has openings 42, instead of notches like those shown at 32 in other views, the cores 22 passing through these openings as the rear wall 10 is swung. These cores are curved in cross section instead of having flat upper sides as shown in other views.
- 35 By reason of the long arms 11 of the rear wall 10 as shown, a radius for the swinging movement of the rear wall is provided sufficiently long that the withdrawal of the cores does not disturb the concrete in the mold.
- 40 The rabbets 45, 46 in block 41 are formed by molding strips indicated at 47, 48 in Figure 9.
- 45 The particular concrete blocks shown by the drawings are building blocks adapted to be fitted together in wall construction.
- 50 A chain 49 limits the rearwardly swinging movement of the rear wall in both constructions, and the coiled spring 50 whose ends are fastened to links of the chain nearer each other than the length of the spring serves to cushion this movement.
- 55 55 The invention being intended to be pointed out in the claims, is not to be limited to or by details of construction or arrangement of any particular embodiment thereof illustrated by the drawings or hereinbefore described.
- 60 I claim:
1. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being pivotally connected with the base independently of the other walls for swinging movements respectively to and from operative closed position, and releasable means for holding said walls in said operative closed position.
  2. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being pivotally connected with the base independently of the other walls for swinging movements respectively to and from operative closed position, and releasable means for holding said walls in said operative closed position including a rod turnably connected with one wall of one of said pairs for vertical and horizontal swinging movements and adapted in one swung position to releasably engage at its free end with the other wall of said pair to hold said pair in operative closed position.
  3. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being pivotally connected with the base for swinging movements respectively to and from operative closed position, and releasable means for holding said walls in said position including a block member pivotally mounted on one wall of one of said pairs and a rod pivotally mounted on said member to turn about an axis at right angles to the axis of the pivotal mounting of said member on said wall and adapted to engage at its free end with the other wall of said pair to hold said pair in operative closed position.
  4. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being pivotally connected with the base independently of the other walls for swinging movements respectively to and from operative closed position, and releasable means for holding said walls in said position including a rod turnably connected with one wall of one of said pairs and having its free end threaded and provided with a nut adapted to adjustably engage the other wall of said pair to hold said pair in operative closed position.
  5. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being swingable on their pivotal connections to and from operative closed position.
  6. A mold structure comprising a base and a mold supported thereby having a bottom, a wall pivotally connected with the base for swinging movement to and from operative closed position and an inner wall pivotally connected with the bottom for swinging movement about an axis parallel with the axis of the first-mentioned wall's movement, and adjustable stops between said walls for limiting their approaching movement.
  7. A mold structure comprising a base and

a mold supported thereby having a bottom, a pair of opposite side mold walls pivotally connected with the bottom for swinging movement to and from operative closed position, a second pair of opposite side walls one of which being a mold wall is pivotally connected with the bottom for swinging movement to and from operative closed position, the other one of said second pair being pivotally connected with the base for swinging movement to and from operative closed position, and an inner wall pivotally connected with the bottom for swinging movement about an axis parallel with the axis of the movement of the wall which is pivotally connected with the base, threaded stops for adjustably limiting the relatively approaching movement of the inner wall and the wall which is connected with the base, releasable means for connecting the side walls in their closed position with the inner wall, and releasable means for holding said second pair in operative closed position.

8. A mold structure comprising a base and a mold supported thereby having a bottom, a pair of opposite side mold walls pivotally connected with the bottom for swinging movement to and from operative closed position, a second pair of opposite side walls one of which being a mold wall is pivotally connected with the bottom for swinging movement to and from operative closed position, the other one of said second pair carrying the core of the mold on its inner side and being pivotally connected with the base for swinging movement to and from operative closed position, and an inner wall having an opening receiving said core and being pivotally connected with the bottom for swinging movement about an axis parallel with the axis of the movement of the wall which is pivotally connected with the base, releasable means for holding the first-mentioned pair of walls in connected relation with the inner wall and releasable means for holding the second-mentioned pair of walls in operative closed position.

9. A mold structure comprising a base and a mold supported thereby having a bottom pivotally connected with the base for swinging movement between material-receiving and work-discharging positions of the mold, a pair of opposite side mold walls pivotally connected with the bottom for swinging movement to and from operative closed position, a front wall pivotally connected with the bottom for swinging movement to and from operative position, and a rear wall pivotally connected with the base independently of the other walls for swinging movement to and from operative closed position, and releasable means for holding the walls in operative closed position.

60 10. A mold structure comprising a base and

a mold supported thereby having a bottom pivotally connected with the base for swinging movement rearwardly to a position wherein the mold receives the material to be molded and forwardly to a position wherein the molded work is discharged from the mold, a pair of opposite side mold walls pivotally connected with the bottom for swinging movement to and from operative closed position, a front wall pivotally connected with the bottom for rearwardly-forwardly swinging movement to and from operative closed position, a rear wall pivotally connected with the base independently of the other walls for forwardly-rearwardly swinging movement to and from operative closed position and an inner wall pivotally connected with the bottom for forwardly-rearwardly swinging movement to stopped positions, and releasable means for holding the walls in operative position.

11. A mold structure comprising a base and a mold supported thereby having a bottom pivotally connected with the base for swinging movement rearwardly to a position wherein the mold receives the material to be molded and forwardly to a position wherein the molded work is discharged from the mold, a pair of opposite side mold walls pivotally connected with the bottom for swinging movement to and from operative closed position, a front wall pivotally connected with the bottom for rearwardly-forwardly swinging movement to and from operative closed position, a rear wall carrying the core of the mold on its inner side and pivotally connected with the base for forwardly-rearwardly swinging movement to and from operative closed position and an inner wall having an opening receiving said core and pivotally connected with the bottom for forwardly-rearwardly swinging movement to stopped positions, and releasable means for holding the walls in operative position.

12. A mold structure comprising a base and a mold supported thereby having a bottom, a pair of opposite side mold walls pivotally connected with the bottom for swinging movement to and from operative closed position and a second pair of opposite side walls one of which being a mold wall is pivotally connected with the bottom, the other one of said second pair being pivotally connected with the base independently of the other walls for swinging movements respectively to and from operative closed positions, and releasable means for holding all the walls in their operative closed positions including a pair of rods swingably connected at one end with one wall of one of said pairs and adapted to engage at their free ends the other wall of said pair and to engage in their middles the walls respectively of the other pair of walls to hold all the walls in their operative closed positions.

JOHANNES T. SENTROP. 60
